SUPPORTING BASE FOR A WORKTABLE OR THE LIKE

Max T. Voigt, Reading, Pa., assignor to American Safety Table Co., Inc., Mohnton, Pa., a corporation of Pennsylvania

Application February 6, 1948, Serial No. 144,325

Term of patent 14 years

(Cl. D33—14)

To all whom it may concern:

Be it known that I, Max T. Voigt, a citizen of the United States, and a resident of Reading, county of Berks, State of Pennsylvania, have invented a new, original, and ornamental Design for a Supporting Base for a Worktable or the like, of which the following is a specification, reference being had to the accompanying drawing, forming a part thereof, wherein;

Figure 1 is a perspective view of a supporting base for a worktable or the like, showing my new design;

Figure 2 is a vertical sectional view as taken on the line 2—2 of Figure 1; and

Figure 3 is a fragmentary rear perspective view of one end of the supporting base as shown in Figure 1, the opposite ends of the supporting base being of identical construction.

I claim:

The ornamental design for a supporting base for a worktable or the like, as shown.

MAX T. VOIGT.
